[57] CLAIM

The ornamental design for a stool, as shown and described.

DESCRIPTION

FIG. 1 is a front left perspective view of a stool showing my new design;

FIG. 2 is a side view, the opposite side being a mirror image thereof;

FIG. 3 is a front elevational view thereof;

FIG. 4 is a rear elevational view thereof; and,

FIG. 5 is an enlarged top view thereof.

The bottom elevational view of the design is not shown and forms no part of the claim design. The dashed lines represent environmental elements only and form no part of the claimed design.

The fragmented pattern shown on the seat member is understood to repeat uniformly throughout the circumscribed area.
